CLOSURE

Filed Sept. 4, 1929

Inventor:
Abraham Singer Karper

UNITED STATES PATENT OFFICE

ABRAHAM SINGER KARPER, OF NEW YORK, N. Y.

CLOSURE

Application filed September 4, 1929. Serial No. 390,382.

This invention relates to spring supported closure members for receptacles and the like and particularly waste receptacles.

It is an object of the invention to provide a closure of this type which is operable from any direction and which automatically resumes a closed position when at rest.

A further object of the invention is to provide a closure of this type which is relatively simple and rugged in construction and will operate over a long period of time with freedom from mechanical defect.

With these and further objects in mind, reference is had to the attached sheet of drawing in which:

Fig. 1 is a side elevation of one type of receptacle with a closure in place thereon,

Fig. 2 is a cross-section of the receptacle closure shown in Fig. 1,

Fig. 3 is a plan view of one type of receptacle which may be employed for use with the closure here described, and

Fig. 4 is a top view of the closure member taken along the lines 4—4 of Fig. 2.

Referring now to the drawing, numeral 1 represents a circular band member provided with a bevelled flange. Secured to this band or ring, are arms 3 which extend radially to a central axis or hub portion 2. Supported in said hub is an upright stem 4 which is secured thereto in any suitable manner. The upper end of this stem may be screw threaded as at 5, but in any event, is formed with a collar portion 11 which supports a coiled spring 10. This spring coacts with a conical cover portion 6, and holds it in position as at 12. At the top of the upright stem and cooperating with the screw thread portion thereof, may be secured a translucent element 8 while suitable electric means may be disposed therein so as to illuminate the top of the closure.

The receptacle, in order to facilitate the emptying of waste from its interior, may be formed with a side door 14, and a smaller interior container 16 may be placed inside of the receptacle and removed through this opening. The door is formed with an arm or brace 15 which rests on the top of the inner

receptacle and tends to hold the same in place when the door is shut.

In operation, a user of the receptacle presses against any side of the cover portion 6 causing it to pivot at 12 on its spring suspension and swing inwardly. The waste is then allowed to fall into the interior of the receptacle after which the pressure on the cover member is withdrawn and the same assumes its rest or closed position. The illuminated member at the top of the closure can be supplied with electric current or other suitable lighting means by any well known method.

From the foregoing, it will be understood that among others, the several objects of the invention, as specifically aforesaid are achieved. It is apparent that numerous changes in construction and rearrangement of the parts may be resorted to without departing from the spirit of the invention as defined by the claims.

Having described my invention, what I claim as new and desire to secure by Letters Patent is:

1. A closure of the character described, comprising a container engaging portion and a cover portion and yielding means forming the sole connection between the parts and positioned to hold said cover portion above said container engaging portion and in registry therewith.

2. A closure of the character described comprising a container engaging portion and a cover portion and a flexible spring member forming the sole connection between the parts and positioned to hold said cover portion above said container engaging portion and in registry therewith.

3. A closure of the character described comprising a container engaging portion and a cover portion, supporting means carried by and extending upwardly from said container engaging portion and a spring secured at one end to said supporting means near the top thereof, the other end forming the sole support for said cover portion whereby the latter is held above said container engaging portion and in registry therewith.

4. A closure including, in combination, a

container engaging ring, supporting means secured to said ring and extending upwardly therefrom, a shoulder formed in said supporting means near the top thereof, a coiled 5 spring resting at one end on said shoulder and a cover portion above said ring and in registry therewith, said cover being supported solely by the free end of said spring.

5. A closure including, in combination, a 10 container engaging ring, a support secured to said ring and extending upwardly therefrom, a cover portion adapted to be disposed above said ring and in registry therewith and flexible means carried by said support 15 and coupled to said cover to maintain the parts in proper relationship, said flexible means providing the sole support for said cover portion and being disposed entirely within the same.

20 6. A closure of the type described comprising an annular container engaging member, radially disposed arms extending inwardly therefrom, a support carried by said arms and rising upwardly therefrom, a cover portion adapted to be placed above said annular member and in registry therewith and a spring carried by said supporting means near the top thereof and coupled to said cover portion, said spring providing the sole means 25 for maintaining said parts in proper relationship.

7. A receptacle of the character described comprising a container body, a closure member for association therewith and adapted to 30 swing freely with respect to said container, a side door formed in the latter to afford access to the interior of the can, an inner receptacle supported by and cooperating with said door for movement into and out of 35 registry with said container, and a brace carried by said door and adapted to maintain said inner receptacle in position with respect thereto.
